CLAIM

The ornamental design for a satellite dish stabilizing clamp, as shown and described.

DESCRIPTION

FIG. 1 is a top perspective view of a satellite dish stabilizing clamp showing my new design;

FIG. 2 is a side elevational view of FIG. 1;

FIG. 3 is a top plan view of FIG. 1;

FIG. 4 is a bottom plan view of FIG. 1;

FIG. 5 is a right and left elevational view of FIG. 1; and,

FIG. 6 is an enlarged fragmentary view taken on line 6—6 of FIG. 3 shown for illustrative purposes only.
